(57) **CLAIM**

The ornamental design for a tree felling head, as shown and described.

DESCRIPTION

FIG. 1 is a front view showing our new design for a tree felling head,

FIG. 2 is an underside view,

FIG. 3 is a top view,

FIG. 4 is a left side view,

FIG. 5 is a rear view,

FIG. 6 is a right side view; and,

FIG. 7 is an isometric view.

The broken lines depict portions of the tree felling head that form no part of the claimed design.
